1

Latin name of the genus and species of the plant named:
Chrysanthemum×morifolium.

Variety denomination: 'Glowing Ember'.

FIELD OF THE INVENTION

The present invention relates to a new *Chrysanthemum* plant botanically known as *Chrysanthemum×morifolium*, and hereinafter referred to by the varietal name 'Glowing Ember'.

BACKGROUND OF THE INVENTION

'Glowing Ember' is a product of a planned breeding program that focuses on obtaining new cultivars of garden *Chrysanthemums* in a range of flower colors that bloom late in the season after other fall mums have passed. These plants exhibit superior winter hardiness suitable for northern climates and provide much needed food for bees and beneficial insects.

'Glowing Ember' originated from an open pollinated cross in 2005 at Dunvegan Nursery in Coatesville, Pa. The female parent was the species *Chrysanthemum indicum*, a semi-double daisy form with yellow and pink ray florets, and medium upright habit. The male parent of 'Glowing Ember' is *Chrysanthemum×koreanum* 'Sheffield', with single flowers of pink floret color, and a well-branched habit, producing an abundant amount of pollen. 'Glowing Ember' was selected as one flowering plant within the progeny of the stated cross in November 2005, and grown out of doors in Coatesville, Pa.

The first act of asexual reproduction of 'Glowing Ember' was accomplished when vegetative cuttings were propagated from the initial selection in April 2008, in a controlled environment in Coatesville, Pa.

SUMMARY OF THE INVENTION

'Glowing Ember' has a semi-double form with orange ray florets with a gold edge, uniform habit and flowering response

(57) **ABSTRACT**

A new cultivar of *Chrysanthemum* plant botanically known as *Chrysanthemum×morifolium*, and commercially referred to by the varietal name 'Glowing Ember'. The new cultivar has a semi-double form with orange ray florets with a gold edge, uniform habit and flowering response that is late, strong stems, medium green foliage color, good garden habit, and excellent shelf life.

3 Drawing Sheets

2

that is late, strong stems, medium green foliage color, good garden habit, and excellent shelf life.

Horticultural examination of plants grown from cuttings of the plant initiated in April 2008 and continuing thereafter, has demonstrated that the combination of characteristics as herein disclosed for 'Glowing Ember' are firmly fixed and are retained through successive generations of asexual reproduction.

'Glowing Ember' has not been observed under all possible environmental conditions. The phenotype may vary significantly with variations in environment such as temperature, light intensity and day length.

'Glowing Ember' has not been made publically available for more than one year prior to this filing.

The following traits have been repeatedly observed and are determined to be basic characteristics of the new variety. The combination of these characteristics distinguishes 'Glowing Ember' from all other varieties of *Chrysanthemum* known to the inventors.

**BRIEF DESCRIPTION OF THE
PHOTOGRAPHS/DRAWINGS**

The accompanying photographic drawing shows typical flower and foliage characteristics of 'Glowing Ember' with colors being as true as possible with an illustration of this type.

FIG. 1 shows a plant of the cultivar in full bloom;
FIG. 2 shows the various stages of bloom of the new cultivar; and

FIG. 3 shows the foliage of the new cultivar.

DETAILED BOTANICAL DESCRIPTION

The plant descriptions and measurements were taken in St. Albans, VT in October 2010 under greenhouse conditions. The aforementioned photographs were taken in a studio in St. Albans, Vt. in October 2010. The plants were started and

grown in Coatesville, Pa., then shipped to St. Albans, Vt. in July 2010. Plants were grown under greenhouse conditions typical for herbaceous perennial plant production. Color references are made to The Royal Horticultural Society Colour Chart (R.H.S.) 2007.

TABLE 1

Difference between the new variety 'Glowing Ember' And 'Sheffield'		
	'Glowing Ember'	'Sheffield'
Flower Color:	Orange	Pink
Flower Size:	5-6 cm	7-8 cm
Plant Height:	40-44 cm	60-75 cm
Bloom Time:	October-November	September-October

Plant:

Form, growth and habit.—Herbaceous garden-type; medium and upright, freely branching. Suitable for garden and pot production.

Plant height.—10-15 cm.

Plant height (inflorescence included).—52-56 cm.

Plant width.—40 cm.

Roots:

Number of days to initiate roots.—6 days at 18 degrees C.

Number of days to produce a rooted cutting.—12 days at 18 degrees C.

Type.—Fine, fibrous, free branching.

Color.—RHS N155A.

Foliage:

Arrangement.—Alternate, simple.

Immature leaf color upper surface.—RHS N137C.

Lower surface.—RHS 138B.

Mature leaf color, upper surface.—RHS 137A.

Lower surface.—RHS 137C.

Length.—4.5-5.5 cm.

Width.—4.5-5.3 cm.

Shape.—Ovate.

Base shape.—Acuminate.

Apex shape.—Mucronulate.

Margin.—Palmately lobed, somewhat serrate.

Texture, upper surface.—Glabrous.

Lower surface.—Pubescent.

Color of veins, upper surface.—RHS 139D.

Color of veins, lower surface.—RHS 139D.

Petiole color.—RHS 146A.

Length.—3-4 cm.

Diameter.—0.2-0.3 cm.

Texture, upper surface.—Glabrous.

Lower surface.—Pubescent.

Stem:

Quantity of main branches per 2 year old 2 gallon plant.—32.

Quantity of leaves per branch.—18-20.

Color of stem.—RHS 146D.

Length of stem.—40-44 cm.

Diameter.—0.4-0.5 cm.

Length of internodes.—1.6-2.2 cm.

Texture.—Glabrous.

Color of peduncle.—RHS 146A.

Length of peduncle.—6-7 cm.

Peduncle diameter.—0.2 cm.

Texture.—Glabrous.

Inflorescence:

Type.—Composite type, solitary inflorescence (decorative-type) borne terminally above the foliage, ray florets arranged acropetally on a capitulum.

Quantity of short days to flowering (response time).—55 days.

Quantity of inflorescences per stem.—16-18.

Lastingness of individual blooms on the plant.—35 days.

Fragrance.—Slight-none.

10 Bud: (just before opening/showing color):

Color.—RHS 138B.

Length.—1-1.2 cm.

Width.—0.8-1.2 cm.

Shape.—Oblate

Immature inflorescence:

Diameter.—4.5 cm.

Color of ray florets, upper surface.—RHS 45A, margins (0.1 cm) RHS 13B.

20 Lower surface.—RHS N35B, margins (0.15-0.2 cm) RHS 13C.

Mature inflorescence:

Diameter.—5.6-6.0 cm.

Total diameter of disc.—1.5 cm.

Ray florets:

Average quantity of florets.—42-46.

Color of florets, upper surface.—RHS 26D.

Lower surface.—RHS 35C.

Length.—2.2-2.6 cm.

Width.—0.5-0.6 cm.

Shape.—Oblong.

Apex shape.—Irregularly rounded.

Margin.—Entire.

Texture, upper surface.—Papillose.

Lower surface.—Papillose.

Disc florets:

Average quantity of florets.—Approximately 215-220.

Color of florets.—RHS 9B.

Length.—0.7 cm.

Width.—0.2 cm.

Shape.—Tubular, elongated.

Apex shape.—Acute, 5 pointed.

Phyllaries:

Quantity.—About 26-30.

Color, upper surface.—RHS 141B, with RHS 143D margins which become papery and opaque.

Lower surface.—RHS 143B, with RHS 143D margins which become papery with age and opaque.

Length.—0.8-1.1 cm.

Width.—0.4-0.6 cm.

Shape.—Lanceolate.

Apex shape.—Acute

Base.—Fused

Margins.—Entire, becoming papery with age.

Texture, upper surface.—Glossy and smooth.

Lower surface.—Pubescent.

Reproductive organs:

Pistil.—1.

Length.—0.8 cm.

Style color.—RHS N144C.

Stigma color.—RHS 13A.

Stigma shape.—Bi-parted.

Ovary color.—RHS 145D.

Stamens.—4.

Color of filaments.—RHS N144C.

Length of filaments.—0.3 cm.

US PP23,379 P3

5

Anther color.—RHS 12B.

Anther length.—0.1 cm.

Anther shape.—Oblong.

Color of pollen.—RHS 14B.

Pollen amount.—Slight-Moderate.

Fertility seed set.—Has not been observed on this hybrid.

6

Disease/pest resistance: Disease susceptibility or resistance has not been observed on this hybrid.

What is claimed is:

1. A new and distinct variety of *Chrysanthemum* plant named 'Glowing Ember', substantially as illustrated and described herein.
